UNITED STATES PATENT OFFICE.

FREDERICK WILLIAM STARK, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A SPOON OR ANALOGOUS ARTICLE.

Application filed January 19, 1924. Serial No. 8,357. Term of patent 14 years.

To all whom it may concern:

Be it known that I, FREDERICK WILLIAM STARK, a citizen of the United States, residing at Meriden, in the county of New Haven, State of Connecticut, have invented a new, original, and ornamental Design for a Spoon or Analogous Article, of which the following is a specification, reference being had to the accompanying drawing, forming a part thereof.

The figure is a front elevation of a spoon showing my new design.

I claim:

The ornamental design for a spoon or analogous article substantially as shown.

FREDERICK WILLIAM STARK.
